UNITED STATES PATENT OFFICE

AIMÉ MATHÉ, OF PARIS, FRANCE, ASSIGNOR TO HARTFORD-EMPIRE COMPANY, OF HARTFORD, CONNECTICUT, A CORPORATION OF DELAWARE

CLOSURE FOR GLASS-GATHERING OPENINGS

Application filed August 10, 1926, Serial No. 128,507, and in France September 8, 1925.

My invention relates to glass gathering apparatus in which a mold or other gathering receptacle is introduced directly into the glass furnace, or into a chamber communicating 5 with the glass furnace, for the purpose of withdrawing a charge of glass for subsequent treatment.

The great difficulty in the use of automatic glass-gathering machines of this character 10 resides in the overheating of the molds or other gathering receptacle as a result of their direct contact with the atmosphere of the furnace, and the overheating of other parts of the machine that are located in the immediate 15 vicinity of the furnace, as a result of the opening of the furnace during the gathering operation. The workmen who look after the operation and the maintenance of the machines are likewise subject to inconvenience 20 through the radiation of heat from the furnace when the gathering hole is open.

The present invention has for its object an arrangement whereby these difficulties are avoided. To this end, the closure of the gathering 25 opening of the furnace consists of a box open at its rear and bottom sides and placed in the gathering opening. This box is advanced somewhat into the interior of the furnace for the gathering operation so as to uncover the surface of the pool of glass where the gathering is to take place, without putting the interior of the furnace in communication with the outside.

This box is preferably disposed in the gathering opening in such a way that its inner wall is in line with the interior of the furnace wall, so as to thereby completely avoid any recess in the interior of the furnace. These recesses would prevent obtaining homogeneous 40 and hot glass in the pool. In case of a door placed in line with the outer wall of the furnace or outside of the furnace, the gathering opening forms, in effect, a recess in which the air becomes cooled through contact with the door, thereby preventing the radiation from the crown upon the pool of glass in the immediate neighborhood of this recess and cooling the surface of this pool of glass by the movement of the cold air contained 45 in the recess.

The box is preferably metallic, with a facing or block of refractory material on its side which is directed toward the interior of the furnace, and this box is provided with means for circulating cooling water. This circulation of water can be omitted if the box is composed entirely of a block of refractory material.

This closure arrangement for the gathering opening can be operated by any suitable means, for example, by a lever, a pedal, a counterweight, a pneumatic cylinder, etc. It is preferably operated automatically by the movement of the glass machine itself.

The accompanying drawing represents by way of example an embodiment of the invention. Fig. 1 is a vertical sectional view of a furnace, the section being taken through the gathering outlet when the furnace is closed. Fig. 2 is a similar view during the gathering 70 operation and Fig. 3 is a horizontal sectional view, the section being taken on the line 3—3 of Fig. 2.

As shown, in the gathering outlet *a* which extends through the wall of the furnace, is placed a metal box *b* open at its lower side and at its rear or outer side. On the side of this box which is directed toward the interior of the furnace, is secured a block or facing of refractory material *c* intended to protect it. The inner wall of this block *c* is disposed in line with the inside of the furnace wall in the position when the furnace is closed as shown in Fig. 1, so that there does not exist any recess or cavity at the gathering outlet to trap air and communicate with the interior of the furnace. There is thus obtained a radiation of heat from the crown of the furnace upon the molten glass in a regular manner, which insures homogeneous glass.

The box structure is secured to a support *d* which can roll upon rollers *e*. The metallic part of the box is cooled by a circulation of water entering at *f*¹ and discharging at *f*².

This closure arrangement, cooled in the manner described, protects at all times the molds *g* or other gathering members, as well as the workmen, from excessive radiation of heat from the furnace.

For the purpose of gathering the desired 100

quantity of glass the box *b-c* is advanced somewhat into the interior of the furnace as shown in Fig. 2. In its movement it uncovers through its lower part the surface of the pool of glass where the gathering is to take place. Since the lower edge of the box reaches approximately to the level of the glass, only the gathering space is put in communication with the outer air through the gathering opening *a*. All the remainder of the mass of glass is protected by the box against the influence of the outer atmosphere, which results in economy of fuel by reason of the almost complete avoidance of loss of heat.

10 It will be understood that this embodiment of my invention is shown and described only by way of example and that a great number of modifications in detail may be made without departing from the principles of the invention.

15 Thus, for example, the closure structure, instead of being supported by rollers and moving back and forth, may be pivoted around a vertical or horizontal axis. Also, it may be operated in any desired manner.

20

I claim as my invention:

1. The combination with a container for molten glass having an opening in a wall thereof above the glass level through which a glass gathering device may be moved to and from a glass gathering position in the container, of a closure for the opening having a refractory portion adapted to substantially close a portion of said opening, and means for 30 conducting a cooling fluid through said closure.

2. The combination with a container for molten glass having an opening in a wall thereof above the glass level through which a glass gathering device may be moved to and from a glass gathering position in the container, of a closure for the opening having a refractory portion formed with its inner face adapted to be substantially flush 40 with the inner face of the container wall adjacent to said opening when said closure is in position to close said opening, and means for conducting a cooling fluid through said closure without admitting said cooling fluid 45 to the interior of said container.

3. The combination with a container for molten glass having an opening in a wall thereof above the glass level through which a glass gathering device may be moved to and from a glass gathering position in the container, of a closure for the opening having a refractory portion formed with its inner face adapted to be substantially flush with the inner face of the container wall adjacent to said 55 opening when said closure is in position to close said opening, and means for supporting said closure for movement in line with said opening closing position and a non-closing position within

4. The combination with a container for molten glass having an opening in a wall thereof above the glass level through which a glass gathering device may be moved to and from a glass gathering position in the container, of a closure for the opening having a refractory portion formed with its inner face adapted to be substantially flush with the inner face of the container wall adjacent to said opening when said closure is in position to close said opening, means for supporting said closure for movement between said opening closing position and a non-closing position in timed relation with the movements of the glass gathering device.

5. The combination with a container for molten glass having an opening in a wall thereof above the glass level through which a glass gathering device may be moved to and from a glass gathering position in the container, of a closure for the opening having a refractory portion adapted to substantially close the inner end portion of said opening, means for supporting said closure for movement in line with said opening between said opening closing position and a non-closing position within the container, said closure having baffle walls at the top and sides thereof outwardly of said refractory portion for cooperating with the latter when said closure is in its non-closing position in the container to substantially shut off the space above the glass at the gathering station from the space above the remainder of the glass in the container without interfering with movement of the glass gathering device through said opening to and from its glass gathering position at said gathering station.

6. The combination with a container for molten glass having an opening in a wall thereof slightly above the glass level through which a glass gathering device may be moved between a position outside of the container and a glass gathering position in the container, of a closure comprising a hollow body adapted to be moved between a position in the opening and a position above the gathering station in the container, said closure body being open at its bottom and outer end and having a refractory inner end portion adapted to substantially close the inner end portion of said opening when said closure is disposed in said opening, the top and side walls of said closure body being adapted to cooperate with the inner end portion thereof to practically shut off communication between the space above the glass at the gathering station and the space above the remainder of the glass in the container when said closure is in its non-closing position in the container, the space within said closure body and the openings at the bottom and outer end of the closure body being adequate to permit movements of the glass gathering means

through said opening to and from its glass gathering position at said gathering station when said closure is in its non-closing position, and means for operating said closure.

7. In combination with a container for molten glass, having an opening formed therein through which a glass gathering device may be moved to and from a glass gathering position in the container, of a closure for the opening, means for slidably supporting the closure for horizontal rectilinear movement into and out of closed position, said closure and said means being arranged to permit the closure to be moved inwardly of the container to open position, and outwardly of the container to closed position.

8. The combination with a container for molten glass having an opening formed therein through which a glass gathering device may be moved to and from a gathering position, means for slidably supporting said closure for rectilinear movement into and out of closed position, and means carried by said closure for obstructing the passage of air from the exterior of said container into the interior thereof when the closure is in open position.

Signed at Paris this thirtieth day of July, 1926.
